UNITED STATES PATENT OFFICE.

FRANK DE BARBADILLO, OF BALTIMORE, MARYLAND, ASSIGNOR TO EDWARD J. REILLY, OF BALTIMORE, MARYLAND.

DESIGN FOR A SHOE-POLISHING DEVICE.

48,857.

Specification for Design.

Patented Apr. 11, 1916.

Application filed December 12, 1914. Serial No. 876,986. Term of patent 14 years.

To all whom it may concern:

Be it known that I, FRANK DE BARBADILLO, a citizen of the Republic of Peru, residing at Baltimore, Maryland, have invented a new, original, and ornamental Design for a Shoe-Polishing Device, of which the following is a specification, reference being had to the accompanying drawings, forming a part thereof.

Figure 1 is a perspective view of a shoe

polishing device showing my design. Fig. 2 is a side elevation of the shoe polishing device.

I claim:

The ornamental design for a shoe polishing device, as shown.

FRANK DE BARBADILLO.

Witnesses:

LEROY BARRY,
E. MARIE PINNING.
